UNITED STATES PATENT OFFICE

LESLIE E. LONG, OF CHICAGO, ILLINOIS

MACHINE FOR REMOVING HEADS AND FEET OF FOWL

Application filed September 10, 1930. Serial No. 481,001.

This invention relates to certain novel improvements in machines for removing heads and feet of fowl, and has for its principal object the provision of an improved construction of this character which will be highly efficient in use and economical in manufacture.

The salient object of this invention is to provide a sanitary device for expeditiously removing the heads and feet of fowl which will comply with the various health laws governing the handling and cleaning of fowl intended for public sale and consumption as articles of food.

Another object of the invention is the provision of an improved construction of the character described herein which will expeditiously cut off the heads and feet of fowl.

A further object of the invention is the provision of an improved device of the character stated which will expeditiously separate the feet from the head of the fowl after the cutting operation.

A still further object of the invention is the provision of a device which will effectively and in a sanitary way wash the severed feet of the fowl.

An additional object of the invention is the provision of an improved construction which will expeditiously discharge the severed head and feet of the fowl into separate and suitable containers provided therefor.

Other object will appear hereinafter.

The invention consists in the novel combination and arrangement of parts to be hereinafter described and claimed.

The invention will be best understood by reference to the accompanying drawing, showing the preferred form of construction and in which:

Fig. 1 is a side elevational view of a preferred form of construction of my invention;

Fig. 2 is a top plan view taken substantially on the line 2-2 in Fig. 1;

Fig. 3 is a front elevational view taken substantially on the line 3-3 in Fig. 1; and

Fig. 4 is an enlarged sectional view taken substantially on the line 4-4 in Fig. 1.

Referring to the drawing wherein a preferred form of construction of my invention

is illustrated, 10 indicates a platform which is supported by legs 11 which are attached to the platform by means of suitable connecting elements such as rivets or the like 12. At its forward end the platform 10 is supported in any approved manner such as by legs 13, 34 and 16 of a supporting structure embodied in the invention. The legs 13, 34 and 16 are secured together by means of braces 14. It is understood that the legs 13, 34 and 16 and braces 14 may be of any suitable material as will best serve the purpose and in the present instance these portions are joined by means of suitable connecting elements such as rivets 15 or the like.

The top portions of the front legs 16 are beveled angularly upward from the front of my device and the rear legs 13 are similarly beveled, the rear legs 13 being somewhat higher than the front legs 16. Mounted on the front legs 16 by means of the hinge structures 17 is a table 18 which slopes angularly downward toward the front of my device. The hinge structures 17 may be of any approved type as will best serve the purpose of facilitating movement of the table 18 into and out of the position shown in dotted outline in Fig. 1. Attached to the table 18 by means of brackets 19 is a U-shaped arm 20 which is adapted to be engaged in notches 21 formed in the legs 13 when the table 18 is in the position shown in solid line in Fig. 1. When the arm 20 is released from the notches 21 the table 18 is moved upwardly on its hinges 17, for a purpose to be explained hereinafter, by the action of springs 22 which are attached to the table in any suitable manner such as by means of hooks 23 and attached to the legs 16 by means of hooks 24.

Extending between the legs 16 and 13 at each side of the device are cross pieces 25 which are secured to the legs 16 by means of suitable connecting elements such as rivets or the like 26, to the legs 34 by means of rivets 35 or the like, and similarly attached to the legs 13 by means of rivets or the like 27. Journaled in suitable bearings 28 in the cross pieces 25 is a shaft 29 on which is mounted for rotatory movement therewith a circular saw 30 which revolves in a slot 31.

provided in the table 18. Carried by the shaft 29 is a pulley 32. The saw 30 is operated by any suitable source of power and in the present instance an electric motor 33 is provided. The motor 33 is preferably supported by means of a platform 58 which is supported by the cross pieces 14. A vertically extending strip 59 is provided at the front of the machine and attached to this strip by means of hinges 60 is a door 61 which provides access to the motor 33. Surrounding the motor 33 is a suitable housing 62. Extending vertically between the cross pieces 14 and the cross piece 25 are the legs 34 which are attached to the cross pieces 25 and 14 by means of rivets or the like 35. Cross arms 36 are provided between the legs 16 and the legs 34 and these arms are attached to the legs 34 and legs 16 by means of suitable connecting elements such as rivets or the like 37. Bearings 38 are provided in the cross arms 36 and journaled in these bearings is a shaft 39 which is attached to the motor 33 in a manner well understood in the art. Carried by the shaft 39 and rotatable therewith is a pulley 40. Extending between the pulley 40 and the pulley 32 is a belt 41. It is manifest, therefore, that when the motor 33 is actuated the belt 41 will rotate the saw 30. In the use of my invention, which will be explained more fully hereinafter, the bodies of the fowl are drawn upwardly over the table 18 by the operator of the machine who preferably stands on the platform 10. The head of the bird is sawed off as the body of the bird is drawn up over the table 18. The bird is then grasped by the neck and feet and the feet cut off by means of the saw 30. A suitable switch structure may be provided at any convenient point on the device for operating the motor 33.

Provided on the table 18 is a guard 42 for the saw 30. In order to effect the separation of the feet and head of the fowl as the same are cut from the body of the bird and in order to maintain the device in a sanitary condition, I provide the construction which will not be described. In this connection I mount a sprinkler pipe 43 on the table 18 by means of brackets 44 and 45 which are secured to the table by means of screws 47 and 48 or the like. A plurality of spaced apart openings 49 are provided in the pipe 43 and water is led into the pipe 43 from a suitable connection such as a flexible hose attached to the end portion 50 of the pipe, the opposite end being closed by means of a cap 51. It is manifest, therefore, that as water is led into the pipe 43 it will be discharged through the openings 49 onto the table 18 which has a ridge 52 formed on the upper surface and around the periphery thereof.

Formed as depressions in the table 18 are similar troughs 53 which extend from a point adjacent the sides of the saw 30 to the

front and lower edge of the table and it will be seen that as the head of the bird is severed by the saw it will fall into one of the troughs and be carried down the trough by the action of the water from the pipe 43 and the force of gravity, whereas when the bird is grasped by the neck and feet and the feet cut off, the feet will fall into the opposite trough and be similarly carried down the trough by the action of water and the force of gravity. The troughs 53 terminate forwardly in spouts 54. Suitable containers may be provided under each of the spouts 54 for collecting the heads and feet of the fowl as the same are separately discharged from the spout portions 54.

A plurality of slots 55 is provided in each of the troughs 53 adjacent the spout portions 54 and as the water flows down the troughs 53 it falls through the slots 55 into a drain 56 which is closed at the bottom except for an outlet provided therein which will be described presently. The drain 56 is supported by the two troughs 53 and a plurality of pipes 57 which extend through openings provided in the drain 56 and are secured thereto in any suitable manner such as by soldering. At their upper ends the pipes 57 are attached to the table 18 in any suitable manner such as by soldering and the upper ends of these pipes open onto the table 18 so that as water from the pipe 43 is flushed over the table 18 at the sides of and between the troughs 53 this water is carried by the pipes 57 to the drain 56.

The drain 56 has a slotted opening 65 provided in the bottom thereof and this opening extends across the entire length of the drain 56 so as to prevent feathers, blood, dirt, etc., accumulating in the drain. The slotted opening 65 is aligned with a trough 63 which is slidably mounted on and supported by a bracket 64 which is attached to the strips 59 by means of suitable connecting elements such as rivets 66. The trough 63 is wider than the slotted opening 65 and is supported in angular position with respect to the horizontal. At its lower and rear end the trough 63 discharges above a basin 67 which is supported by the braces 14 and suspended therefrom at the bottom of the machine, and as shown in Fig. 2, the trough 63 includes converging side walls 63' which extend back under the machine and provide rapid and adequate drainage into the basin 67. It is manifest, therefore, that the table 18 will be kept in a sanitary condition by the flushing of the water from the pipe 43 thereover while the flushing action of the water will likewise facilitate moving the severed heads and feet of the fowl down the troughs 53.

To facilitate guiding the water into the drain pipes 57 I provide a transversely extending groove 68 which extends across the lower end of the table and into which the

drain pipes 57 open at their upper ends. The groove 68, as best shown in Fig. 3, extends down the sides of the troughs 53 so as to conduct any water not entering the pipes 57 to the slots 55. A similar groove 69 extends 5 parallel with the groove 68 and these grooves effectively carry the water away from the table and prevent the water from the table from flowing into suitable containers (not shown) which may be provided below the 10 troughs 53 for the heads and feet of the fowl.

It is apparent, therefore, that the greater part of the water passing down the troughs 53 will fall through the slots 55 into the drain 56, thence through the trough 63 into the 15 basin 67 while some of the water passing over the table 18 but not through the troughs 53 will pass into the groove 69 and thence to the slots 55 while any water from the table that may flow past the groove 69 will flow into the groove 68 and thence down the pipes 57 into the drain 56 and thence through the trough 63 to the basin 67 in the manner described hereinbefore. In this manner the 20 machine is kept in a sanitary condition which will comply with the various health laws and the inspections provided for the enforcement thereof.

When for any reason either one or both of the troughs 53 become clogged the table 18 30 may be lifted into the position shown in dotted outline in Fig. 1 and this is accomplished by releasing the arm 20 from engagement in the notches 21 which causes the springs 22 to tilt the table 18 thereby releasing the heads or feet of the fowl which may have become temporarily clogged in one or the other of the troughs 53.

From the foregoing description of my invention it is manifest that I have provided 40 a machine which will fulfill the requirements of the various health laws governing the handling of fowl intended for public use as food and which while being simple in construction and operation will expeditiously sever and separate the heads and feet of fowl. It is apparent, therefore, that I have provided a device which while accomplishing its 45 several objects will be labor saving and efficient in use while being economical in manufacture.

While I have illustrated and described the preferred form of construction for carrying my invention into effect, this is capable of 55 variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

65 1. In a machine of the class described, a

supporting structure, a table pivotally mounted on said supporting structure, means providing pivotal connection between said table and said supporting structure, said table including diverging trough members having outlets formed therein, fluid supplying means including a pipe member mounted on said table, means providing connection between said last-mentioned means and said table, a cutting element rotatably mounted between said trough members adjacent the point of divergence of said trough members, and supporting means for said cutting element.

2. In a machine of the class described, a supporting structure, a table pivotally mounted on said supporting structure and inclined at an acute angle with the horizontal, means providing pivotal connection between said table and said supporting structure, means for moving said table in a vertical plane including spring members, retaining means for securing said table in fixed position against the action of said spring members, said table including diverging trough members having outlets formed therein, fluid supplying means including a pipe member mounted on said table, means providing connection between said last-mentioned means and said table, a cutting element rotatably mounted between said trough members adjacent the point of divergence of said trough members, and supporting means for said cutting element.

3. In a machine of the class described, a supporting structure, a table pivotally mounted on said supporting structure, means providing pivotal connection between said table and said supporting structure, said table including diverging trough members having outlets formed therein, a cutting element rotatably mounted between said trough members, operating means for said cutting element including motive power supplying means, means providing connection between said operating means and said cutting element including rotatable means, and supporting means for said cutting element.

4. In a machine of the class described, a supporting structure, a table pivotally mounted on said supporting structure and inclined at an acute angle with the horizontal, means providing pivotal connection between said table and said supporting structure, said table including diverging trough members having a plurality of slots formed therein at the lower end thereof, said table having a plurality of outlet connections including pipe members provided therein at the lower end thereof, a trough member slidably mounted on said supporting structure below said slots and said pipe members, means including a trough member for conducting a fluid from said pipe members and said slots to said slidably mounted trough member, a receptacle providing a basin communicating

with said slideable trough member and mounted on said supporting structure, fluid supplying means including a pipe member mounted on said table at the upper end thereof, said pipe member having a plurality of outlet openings formed therein in spaced apart relationship whereby a fluid directed from said pipe member will be simultaneously distributed over said table and included trough members, a cutting element rotatably mounted between said trough members adjacent the point of divergence of said last-mentioned trough members, operating means for said cutting element, and supporting means for said cutting element.

15 5. In a machine of the class described, a supporting structure, a table pivotally mounted on said supporting structure and inclined at an acute angle with the horizontal, means providing pivotal connection between said table and said supporting structure, means for moving said table in a vertical plane including spring members, retaining means for securing said table in fixed position against the action of said spring members, said supporting structure including a platform provided at the rear of said table, said table including diverging trough members having outlets formed therein, fluid supplying means including a pipe member mounted on said table, means providing connection between said last-mentioned means and said table, a cutting element rotatably mounted between said trough members adjacent the point of divergence of said trough members, and supporting means for said cutting element.

20 6. In a machine of the class described, a table including diverging trough members inclined from the horizontal and having outlets at their lower ends, a cutting element rotatably mounted between said trough members adjacent the point of divergence thereof, means for supplying a cleansing fluid to said table and trough members, and means for diverting said fluid away from said trough members at a point above said outlets.

25 7. In a machine of the class described, a pivotal table including diverging trough members, inclined from the horizontal and having outlets at their lower ends, a cutting element rotatably mounted between said trough members adjacent the point of divergence thereof, means for supplying a cleansing fluid to said table and trough members, means for diverting said fluid away from said trough members at a point above said outlets, and means for pivoting said table and trough members in a vertical arc.

30 60 In testimony whereof I affix my signature.
LESLIE E. LONG.
